SECTIONAL TOY BRIDGE

Paul E. Bleil, Los Angeles, Calif.

Application January 3, 1955, Serial No. 33,801

Term of patent 14 years

(Cl. D34—15)

FIG. 1

FIG. 2

FIG. 3

Fig. 1 is a perspective view of a sectional toy bridge, showing my new design;

Fig. 2 is a plan view thereof; and

Fig. 3 is a side elevational view thereof.

I claim:

The ornamental design for a sectional toy bridge, substantially as shown.
